BUFFET OR SIMILAR CABINET

Robert E. Kjer Jakobsen, Manhattan Beach, Calif., assignor to Virtue Bros. Mfg. Co., Los Angeles, Calif., a corporation of California

Application December 5, 1955, Serial No. 39,161

Term of patent 14 years

(Cl. D33—19)

Fig. 1 is a perspective view of a buffet or similar cabinet showing my new design.

Fig. 2 is an enlarged vertical sectional view of one end of the buffet as taken on line 2—2 of Fig. 1.

The back of the chest portion of the design is rectangular and substantially plain and unornamented.

I claim:

The ornamental design for a buffet or similar cabinet, substantially as shown and described.
